LINEMAN'S PROTECTOR

Franklin L. Pittman, Frankfort, N. Y., assignor
of one-third to John Van Vorst

Application July 28, 1938, Serial No. 221,742

16 Claims. (Cl. 174—5)

The invention relates to devices for protecting linemen against electrical shocks and burns when working on the poles of power lines, and it aims to provide a new and improved device which may be readily carried with the customary linemen's equipment, may be quickly and easily applied when needed, and will not only protect against the wires but against the bracket which carries the wire-supporting insulators.

10 A further object is to provide a novel construction which may be adjusted for use with different brackets regardless of the spacings of the insulators carried thereby.

With the foregoing in view, the invention relates in the novel subject matter hereinafter described and claimed, description being accomplished by reference to the accompanying drawings.

Fig. 1 is a side elevation showing one form of the protector immediately prior to fastening in operative position and prior to attachment of the curtains.

Fig. 2 is a view similar to Fig. 1 but showing one of the curtains attached and illustrating the lower portion of the protector in vertical section.

Fig. 3 is a vertical sectional view on line 3—3 of Fig. 1, all of the curtains, however, being attached.

30 Fig. 4 is a horizontal sectional view on line 4—4 of Fig. 3.

Fig. 5 is a fragmentary perspective view.

Fig. 6 is an elevation of one of the curtains.

Fig. 7 is a view similar to Fig. 2 showing a different construction and omitting the insulators and the bracket.

Fig. 8 is a horizontal sectional view on line 8—8 of Fig. 7.

Fig. 9 is a detail sectional view duplicating a portion of Fig. 8 on an enlarged scale.

40 The protector of Figs. 1 to 6 will first be described. This protector is intended for use with the insulators and bracket shown in a number of said figures and briefly described as follows. 7 denotes a vertically elongated attaching plate having a central vertical ridge 8 through which the bolts 9 pass for securing said bracket to the pole 10. Also secured to the ridge 8 are outwardly projecting arms 11 through which a vertical bolt 12 passes, said bolt extending through the insulators 13 to which the wires 14 are secured by conventional means 15.

45 The protector comprises a vertically elongated longitudinally channeled member molded from rubber or similar material, said member being of

a size to enclose the insulator bracket, the insulators, and portions of the wires immediately adjacent said insulators. The elongated channeled body is denoted in a general way by the reference character 16, said body being preferably closed at both of its ends. At suitable intervals, depending upon the number of wires and insulators, the channeled member 16 is provided with transverse notches 17 which open through the central longitudinal portion of said member, 14 through the side walls of said member, and through one longitudinal ledge portion of said member, but not through the other longitudinal edge portion thereof. These notches permit easy engagement of the protector with the insulator bracket by accommodating the wires 14, it being of course understood that the device is initially placed at the sides of the wires toward the pole 10 and is then moved arcuately into operative position in which it encloses the insulators and the bracket with the wires 14 extending through the notches 17.

50 The longitudinal edge portion of the member 16 through which the notches 17 do not open, is preferably in the form of a vertically elongated connecting strip 18. Another vertically elongated connecting strip 19 is provided to close the open ends of the notches 17 at the other longitudinal edge of the protector, provision being made for connecting the portions of said protector above 30 and below the notches 17, with said strip 19.

In the preferred manner of constructing the invention, three visor-like cowls 20, 21 and 22 and an inverted cowl 23, are all formed integrally at their inner ends with the connecting strip 18, 35 and the connecting strip 19 is pivoted at 24 to the rear or inner end of the cowl 20, said strip being provided with means for temporarily connecting it with the cowls 21, 22 and 23. In the present showing, buttons 25 are provided on the strip 19 for engagement with the buttonholes 26 formed through portions of the cowls 21, 22 and 23.

55 The cowl 20 is provided with an internal supporting lug 20' notched at 20'' to straddle the uppermost of the arms 11, and each of the cowls 21 and 22 is provided with an integral upstanding vertically channeled portion 27 to yieldably grip the rod 12 when the protector is in place, thereby holding the entire protector in place, as well as covering the portions of said rod 12 between the arms 11. At one vertical edge, each of the rod gripping or clip portions 27 is integral with the connecting strip 18 as shown at 28, the other longitudinal edge portion being provided 55

with a flange 29 through which the button-hole 26 is formed. The upper cowl 20 is preferably provided with angular flanges 30 and the cowl 23 with similar flanges 31 all coacting with the strip 18 and the strip 19 in forming a continuous rim or frame rather snugly surrounding the attaching plate 7 of the insulator bracket when the device is in operative position.

Suitable curtains 32 are provided for connection with the cowls 20, 21 and 22 to hang across the notches 17 and cover portions of the wires 14. To permit easy attachment and detachment of these curtains, I preferably provide the cowls with buttons 33 and the curtains with buttonholes 34 engageable with said buttons. The major portion of the protector is applied while the curtains 32 are detached, the strip 19 being outwardly swingable during application. This strip is then swung inwardly and the buttonholes 26 are engaged with the buttons 25, the grip of the portions 27 on the rod 12 serving to effectively hold the protector in place. The curtains 32 may be quickly and easily applied, and the complete assemblage will effectively prevent the lineman 25 from touching the insulators, the bracket or portions of the wires immediately adjacent thereto. When the device has served its purpose, it may be quickly and easily removed and carried with the rest of the lineman's equipment until again 30 needed.

In Figs. 7 and 8, the cowls 20^a, 21^a, 22^a and 23^a are adjustably connected with the strips 18^a and 19^a, permitting vertical adjustment of said cowls for use with different insulator spacings. These 35 cowls are also individually detachable from the strips 18^a and 19^a, permitting use of any required number of said cowls and removal of those not needed, according to the kind of insulator and bracket assembly with which the invention is being used.

For illustrative purposes, to accomplish the adjustability and detachability of the cowls, tongue-and-groove connections are provided between said cowls and the strips 18^a and 19^a, the 45 tongues 25^a being integral with said strips, and the grooves 26^a being formed in the thickened edge portions 26^b of the cowls. The opposite sides of the tongues 25^a are preferably grooved as shown at 25^b, and the walls of the grooves 26^a 50 are ribbed at 26^c to snugly engage the grooves 25^b. All parts being of rubber, the cowls may be snapped off and on at will and they may obviously be adjusted vertically into any desired spaced relation.

Aside from the differences above described, the device of Figs. 7 and 8 is substantially the same as that of Figs. 1 to 6.

It will be seen from the foregoing that novel and advantageous provision has been made for carrying out the objects of the invention, and while preferred details have been disclosed, variations may, of course, be made within the scope of the invention as claimed.

I claim:

- 65 1. A lineman's protector comprising a vertically elongated longitudinally channelled insulating member to enclose vertically spaced bracket-carried insulators and the pole-carried bracket for said insulators, said protector having vertically spaced notches to receive the insulator-carried wires when the protector is applied.
- 70 2. A lineman's protector comprising a vertically elongated longitudinally channelled insulating member to enclose vertically spaced bracket-carried insulators and the pole-carried bracket for

said insulators, said protector having vertically spaced notches to receive the insulator-carried wires when the protector is applied, said notches opening through the front, the sides and one longitudinal edge portion of said channelled member but not through the other longitudinal edge portion thereof, whereby said channelled member may be readily moved into operative position and said longitudinal edge portions may abut the pole, a connector for the portions of said channelled member above and below said notches, said connector extending longitudinally of said one edge of said channelled member, and means for detachably connecting said portions above and below the notches with said connector.

3. A lineman's protector comprising a vertically elongated longitudinally channelled insulating member to enclose vertically spaced bracket-carried insulators and the pole-carried bracket for said insulators, said protector having vertically spaced notches to receive the insulator-carried wires when the protector is applied, said channelled member being provided with clip portions to yieldably grip portions of the insulator bracket to hold the protector in place.

4. A lineman's protector comprising a vertically elongated longitudinally channelled insulating member to enclose vertically spaced bracket-carried insulators and the pole-carried bracket for said insulators, said protector having vertically spaced notches to receive the insulator-carried wires when the protector is applied, said channelled member being formed of resilient material and having integral clip portions to yieldably grip portions of the insulator bracket to hold the protector in place.

5. A lineman's protector comprising a plurality of vertically spaced visor-like insulating cowls to enclose vertically spaced bracket-carried insulators and portions of the pole-carried bracket for said insulators, and vertically extending means connecting said cowls with each other.

6. A lineman's protector comprising a plurality of vertically spaced visor-like insulating cowls to enclose vertically spaced bracket-carried insulators and portions of the pole-carried bracket for said insulators, a vertically elongated connector unitarily connecting said cowls and disposed at the inner ends thereof, a second vertically elongated connector disposed at the inner ends of said cowls, and means for releasably holding said second connector in cowl-connecting position, the two connectors being disposed in spaced relation to lie against the pole at opposite sides of the insulator bracket.

7. A lineman's protector comprising a plurality of vertically spaced visor-like insulating cowls to enclose vertically spaced bracket-carried insulators and portions of the pole-carried bracket for said insulators, some of said cowls being provided with integral clip portions to yieldably grip portions of the insulator bracket to hold the cowls in operative position, and vertically extending means connecting said cowls with each other.

8. A lineman's protector comprising a plurality of vertically spaced visor-like insulating cowls to enclose vertically spaced bracket-carried insulators and portions of the pole-carried bracket for said insulators, said cowls being formed of resilient material, some of said cowls having upstanding integral vertically channelled portions to enclose and yieldably grip portions of the insulator bracket to hold the cowls in operative position, and vertically extending means connecting said cowls with each other.

9. A structure as specified in claim 1; together with insulating curtains connected with said channeled member over said notches and hanging across the latter.
- 5 10. A structure as specified in claim 5; together with insulating curtains suspended from said cowls to hang across the spaces between said cowls.
11. A lineman's protector comprising spaced substantially parallel strips to lie against a pole at opposite sides of an insulator bracket, and vertically spaced insulator covers of insulating material extending from one of said strips to the other and connected with said strips.
- 15 12. A lineman's protector comprising a plurality of vertically spaced insulator covers of insulating material, and means connecting said covers and constructed to allow relative vertical adjustment thereof.
- 20 13. A lineman's protector comprising spaced substantially parallel strips to lie against a pole at opposite sides of an insulator bracket, vertically spaced insulator covers of insulating material extending from one of said strips to the other, and means connecting said covers with said strips and constructed to allow relative vertical adjustment of said covers.
- 25 14. A lineman's protector comprising spaced substantially parallel strips to lie against a pole at opposite sides of an insulator bracket, vertically spaced insulator covers of insulating material extending from one of said strips to the other, and means detachably connecting said covers with said strips and constructed to allow relative vertical adjustment of said covers.
- 15 15. A lineman's protector comprising spaced substantially parallel strips to lie against a pole at opposite sides of an insulator bracket, vertically spaced insulator covers of insulating material extending from one of said strips to the other, and vertical tongue-and-groove connections between said covers and said strips, permitting relative vertical adjustment of said covers.
- 20 16. A lineman's protector comprising a plurality of vertically spaced visor-like insulating cowls to enclose vertically spaced bracket-carried insulators and portions of the pole-carried brackets for said insulators, some of said cowls being provided with internal clip portions to yieldably grip portions of the insulator bracket to hold the cowls in operative position, and vertically extending means connecting said cowls with each other.
- 25
